UNITED STATES PATENT OFFICE.

ELISHA A. GATES, OF SAN DIEGO, CALIFORNIA, ASSIGNOR OF ONE-HALF TO FRANK G. VILA, OF SAN DIEGO, CALIFORNIA.

DESIGN FOR A COMBINED LICENSE AND NUMBER PLATE HOLDER.

Application filed August 25, 1926. Serial No. 18,864. Term of patent 3½ years.

To all whom it may concern:

Be it known that I, ELISHA A. GATES, a citizen of the United States, residing at San Diego, in the county of San Diego and State of California, have invented a new, original, and ornamental Design for a Combined License and Number Plate Holder, of which the following is a specification, reference being had to the accompanying drawing, forming a part thereof.

The figure is a perspective view of a combined license and number plate holder, showing my new design.

I claim,

The ornamental design for a combined license and number plate holder, substantially as shown and described.

In testimony whereof, I have hereunto set my hand at San Diego, California, this 3rd day of July, 1926.

ELISHA A. GATES.
